FLOW-RESPONSIVE DEVICE

Eugene Jacobson, San Francisco, Calif.

Application December 5, 1927, Serial No. 237,879

12 Claims. (Cl. 137—156)

My invention relates to flow-responsive devices and to a variable venturi incorporated therein; and is intended especially for combination with gas water heaters of the "instantaneous" or flow-controlled type, wherein the fuel valve is operated by the flow of water through the heater.

It is the practice in a common form of domestic water heater, to control the gas fuel supply valve by the flow of water through the heater so that the burner flame is turned on or off in response to commencement or cessation of flow of water through the heater. Practically no allowance is made for variations in flow intermediate between zero and maximum demand. In and of themselves, these flow-controlled valves are not capable of regulating the gas fuel supply in proportion to the water demand throughout the range of demand. In actual practice, unless a complicated and costly thermostatic control is superimposed, the effect is to overheat the water while the demand is small, and to underheat the water when a larger flow is used. No entirely satisfactory means has yet been evolved to make these automatically controlled valves proportionately effective over a wide range of demand, and in practice the heater will not function at all when only a small amount of water is being drawn. It is an object of my invention to practically obviate any and all the disadvantages heretofore inherent in the flow-controlled fuel valves of water heaters.

My invention is applicable more broadly than to water heaters alone. In general, it is an object of my invention to provide an improved flow-actuated means for operating valves.

It is an object of my invention to provide a flow-actuated device having a maximum effective range; and it is an important further object of my invention that this large range be attainable at the expense neither of excessive resistance to flow nor of lack of power of actuation.

It is an object of my invention to provide a venturi which is effective over a wide range of variable flow. The significance of this object of my invention is emphasized by the fact that a venturi is inoperative unless the flow is sufficient to keep it full of liquid, and is practically inoperative unless small enough to secure a high velocity of flow therethrough; while if the venturi is made too small, its resistance to large fluid flow is prohibitive. It is an object of my invention to provide a venturi which may be adjusted to accommodate different volumes of flow, and it is a further object of my invention to

provide automatic means for so adjusting the venturi.

It is an object of my invention to teach the design of flow-responsive devices having an improved means for providing any desired flow-responsive characteristics. It is a further object of my invention to provide a flow-responsive device of the character set forth with adjustments for altering certain of its characteristics.

In the interest of conciseness, the above objects have been condensed. Various subdivisions and combinations of these objects are to be expected within the purview of my invention. Further and ancillary objects of my invention will be suggested in the following description and in the use of the device of my invention.

Referring to the drawings:

Fig. 1 is a schematic minified front elevation of a water heater embodying my invention. Fig. 2 is a median longitudinal section of the valve-operating portion of my invention removed from the water heater. Fig. 3 is a section similar to that of Fig. 2 of a modified form of my invention. Figs. 4 and 5 are elevations of the tip fragments of two different shaped cores alternative to that illustrated in Fig. 3.

A water heater (Fig. 1) of the instantaneous or flow-controlled type, is formed essentially of a casing 1, a water coil 2, a main gas burner 3, and a pilot burner 4 (shown dotted in Fig. 1). A water outlet pipe 5 is provided from the heater, and is connected in conventional manner to the hot-water taps served by the heater. A cold water inlet pipe 6, 6' is adapted to serve the heater from the city or other pressure mains. A gas inlet pipe 7 is provided to supply fuel to the burners 3 and 4, and a gas valve 8 is provided in the supply line 7 for regulating the fuel supply to the burners. These elements are conventional and well-known in the water heater art, and need not be described in detail.

Flow-responsive means are provided for controlling the valve 8 to regulate or determine the fuel supply and therefore the heat input to the water heater. Interposed in the pipe-line 6, 6' supplying water to the heater, is a Venturi passage (Fig. 2 or 3) formed of a pipe-like cast or otherwise suitably formed member 10 having its bore or passage gradually and smoothly reduced from a maximum at each end to a minimum at the throat or constricted portion 10a of the venturi. Whenever water is drawn through the heater, it must flow through the venturi. This flow through the venturi causes a reduction of pressure at the throat 10a, and produces a sharp

difference of pressure (proportional to the square of the flow) between the constricted and unstricted portions of the Venturi passage. Pressure-responsive means are then connected into the venturi for actuating the valve 8. Due to the remarkable characteristics of the venturi, the venturi difference of pressure may be made very great without appreciably increasing the resistance to flow. In fact, by properly proportioning the Venturi passage, an actual negative pressure or partial vacuum may be set up at the throat of the venturi; while the pressure at all other points such as at a hot water tap in the line 5, remains almost unchanged at the normal city water pressure. It is emphasized that the Venturi action is not a throttling effect and that the Venturi pressure difference would be set up even though the pressure at the hot water tap were no less than that in the water mains. It is one important object of my invention to avoid undue loss of pressure between the mains and the hot water tap.

Pressure-responsive means are provided for harnessing this Venturi effect. An expansible-fluid chamber (Fig. 2 or 3) is formed by a cast or otherwise suitably formed cylinder 12 having a removable head 12'; and the movable wall of the expansible-fluid chamber is constituted by a piston or plunger 13. The plunger 13 is preferably fabricated of a pair of discs 13' and 13'' centrally bored and threaded to screw upon the threaded portion 14' of a plunger rod 14. Two annular plunger leathers 13''' and 13'''' are clamped between the discs and extend out into sealing engagement with the wall of the cylinder 12. The plunger is assembled by first screwing one disc 13' up to the desired point of the threaded portion 14', then positioning the two leathers, and then screwing the other disc 13'' tight up against them. The threaded portion 14' is made long enough to permit adjustment of the position of the plunger along the rod. The discs have their opposed radial faces shaped to form a central cup or stuffing box to retain string or other suitable packing 13'' for preventing leakage along the rod 14.

An ingenious arrangement of pressure-responsive means has been selected as most suitable for the purposes of this invention. An eccentric threaded opening in the head 12' of the cylinder, if provided to receive the end of the water supply pipe 6 from the city mains. The head end of the cylinder is thus at all times exposed to the pressure in the water mains, and is therefore the high pressure end of the cylinder. A central threaded opening in the head 12', is adapted to receive the threaded lower high pressure end of the Venturi member 10. The lower or low pressure end of the cylinder 12 is connected by piping 16, into the throat 10a of the venturi. The piping 16 is preferably fabricated of small gauge copper tubing and standard connections therefor such as are commonly employed for gasoline lines in automobiles.

All water passing through the water heater, must flow into this high pressure end of the cylinder and out through the venturi, and this flow through the venturi causes the pressure at the throat 10a to drop below that in the high pressure end of the cylinder 12. This reduction of pressure is communicated by the piping 16 to the low pressure end of the cylinder, thereby inducing movement of the plunger 13 toward the low pressure end of the cylinder. The reduction of pressure, and therefore the force tending to

move the plunger, becomes greater as the flow is increased. Conversely, when flow ceases the pressure at the throat 10a becomes equal to the pressure in the city mains, and the pressure on both sides of the plunger 13 then becomes equal. 5

An adjustable helical spring 17 between the low pressure end of the cylinder and an adjusting nut 17' on the plunger rod 14 urges the plunger counter to the pressure forces imposed thereon, so that the device will return toward 10 inoperative position as soon as flow through the venturi is reduced.

The motion of the plunger 13 is transmitted to the gas valve 8 by the plunger rod 14, the lower small diameter end of which extends out through 15 a stuffing box 18 in the low pressure end of the cylinder. The plunger rod is in line with the stem 8' of the gas valve, so that the gas valve is opened by movement of the plunger 13 toward the low pressure end of the cylinder. 20

The end of the plunger rod 14 outside the stuffing box 18 is threaded to receive an internally threaded sleeve 19 (Fig. 3) which is provided to control the clearance between the plunger rod 14 and the valve stem 8'. A lock nut 20 is 25 provided for the sleeve 19.

The Venturi pressure difference is well adapted to actuation of the fuel valve 8, and is found to control the valve over a far greater range of flow than any such device heretofore employed in 30 water heaters.

Means have been provided in addition, to still further increase the range of effectiveness of the venturi for different water flow quantities. A tapered core 21 (Fig. 2) within the Venturi passage, 35 is movable axially to vary the effective area of the passage to accommodate different flow quantities. When the taper of the core 21 is suitably formed with relation to the normal taper of the venturi, as exemplified in Figs. 2, 3 and 5, the 40 relative constriction at the throat 10a may be increased or decreased so as to adjust the Venturi effect at will and independently of the flow, by the simple adjustment of moving the core axially in the venturi. While I prefer to employ a ta- 45 pered core and constricted conduit to form a variable venturi, I recognize that it would be possible to substitute a tapered conduit and bulbous core to produce a Venturi effect.

A slender integral extension 21' of the core 21 50 extends out beyond the venturi, and is threaded at its outer end for reception in the threaded bore of a pipe plug 22. A knurled adjusting head 23 is secured to the free end of the extension 21', and a combined stuffing box and lock nut 24 is 55 provided to prevent leakage past the pipe plug and to lock the core in adjusted position. The pipe plug 22 is received in and supported by an offset-T pipe fitting 25 which may be cast as shown, or might be assembled of standard parts 60 by combining a plain T and L. These piping connections are modifiable by the pipe-fitter to suit the particular installation of the device of my invention.

In the modified embodiment of Fig. 3 the Ven- 65 turi core 14'' has no threaded extension analogous to the portion 21', and means are provided for automatically moving the core to adjust the size of Venturi passage in response to the flow therethrough. The Venturi core 14'' instead of being 70 manually adjustable, is formed as an integral extension of the plunger rod 14 and is therefore constrained to move with the plunger 13.

In operation, as flow through the system increases, the plunger 13 is forced downward, there- 75

by partially withdrawing the attached tapered core 14" and thus increasing the size of the Venturi passage to accommodate the larger flow. In this form of my invention, movement of the core is automatically controlled by the Venturi pressure difference, and this movement in turn alters the Venturi size. Therefore the movement and pressure variation are intimately interrelated, and are both dependent upon the relative 5 tapers and curvatures of the venturi and core. By suitably proportioning the curvature and taper of the core, movement of the rod 14 may be made any desired function of the water flow. In designing an automatically variable venturi of this 10 type for any particular application, the proportions of the parts will be determined by the particular characteristics desired. Thus, for example, the movement of the rod 14 may be made directly proportional to or may be made any 15 simple or complex function of the flow by suitably forming the Venturi core. Where large movement of the rod is desired over any part of its traverse, that part of its taper will be made very gradual, and where small movement 20 is desired, the taper will be made sharper.

In this particular application of the venturi of my invention the following characteristics of motion are desired. No motion at all is desired until the water flow exceeds a leakage dribble. 25 Therefore the maximum diameter of the core 14" is made slightly smaller than the minimum diameter of the venturi. As soon as the water flow exceeds a leakage dribble, a large initial movement of the rod 14 is desired to take up necessary 30 clearance in the valve-operating mechanism and to open the gas valve to "low flame" position. Therefore the maximum diameter portion of the core is carried substantially without taper for a considerable distance. In order to avoid excessive opening of the gas valve, the second stage 35 of movement of the rod 14 must be relatively small for a given increase of water flow. Therefore the tapered portion of the core is made relatively steep. (For any given main pressure 40 and flow, and neglecting friction, the Venturi pressure difference equals $K \div (d_1^2 - d_2^2)^2$; where K is a constant, d_1 is the diameter of the Venturi throat and d_2 is the diameter of that portion of the core which is at the throat.)

45 The spring tension and position of the plunger on the rod 14, and the clearance between the rod 14 and gas valve 8, may all be adjusted. Where different Venturi characteristics are desired however, a different shaped core must be substituted 50 for the core 14". Before any particular design of a device of my invention is thrown into production the most suitable shape of core should be determined by calculating the diameters necessary to produce the required characteristics 55 at several spaced positions of the core. A number of different cores 14a, 14b, etc. such as are illustrated fragmentarily in Figs. 4 and 5, will ordinarily be supplied with each variable venturi intended for application at different times to 60 actuate different devices. Thus the venturi as a universal device is suitable at one time for example to operate a valve, and at another time to operate a meter, electric switch, or other device; it being necessary merely to substitute a core 14a, 14b, or etc. for the core 14", to produce the desired modified characteristics. The core 14b of Fig. 5 is what I call a double or complex core in that two successive or distinct sets of Venturi characteristics are attainable by 65 axially moving either tapered portion x or y into

the field of the throat 10a of the venturi. By pluralizing the number of tapers on a single core, it is possible to attain any number of different characteristics in a single instrument; it being necessary merely to alter the limits of movement 5 of the core as by altering the position of the plunger 13 thereon. It is, of course, possible to consider these successive tapers a continuous curve of highly complex form, and to permit a corresponding complex Venturi characteristic, 10 this being governed as before, solely by the limits of axial motion which are set for the core. Having taught the basic principles involved, and at least one specific application of these principles, it is deemed within the purview of my invention 15 to alter the shape of core employed, and the limits of movement of the core to produce the desired characteristics to suit the particular application of the device of my invention.

I have described one embodiment of my invention in detail, but it is emphasized that this embodiment is illustrative and not inclusive of all the forms my invention may assume. Certain of the objects, or certain portions or combinations of the objects of my invention may be 20 attained with the use of less than all its advantageous features or with modifications within its purview. It is petitioned that my invention be limited only by the claims constituting its 25 final determination.

30 I claim:

1. In a variable venturi, resilient means normally tending to increase the effectiveness of the venturi, and means controlled by said venturi for decreasing the effectiveness of the venturi. 35

2. An automatically variable venturi comprising a conduit member and a core member mounted for relative movement to vary the effectiveness of said venturi; the movable one of said members being positioned and arranged for movement in the direction of fluid flow through the venturi to increase Venturi effectiveness and counter to said direction of fluid flow to decrease Venturi effectiveness; and means responsive to 40 said fluid flow for moving said movable member. 45

3. An automatically variable venturi comprising a conduit member and a core member formed to leave a Venturi passage therebetween and mounted for relative movement to alter the constriction of said venturi; the movable one of 50 said members being positioned and arranged for movement in the direction of fluid flow through the venturi to constrict the Venturi passage and counter to the direction of fluid flow to expand the Venturi passage; and means responsive to 55 said fluid flow for moving said movable member.

4. In combination, a conduit and a movable Venturi-control core within said conduit; said conduit and core being relatively formed and positioned to form a Venturi passage therebetween; 60 an expandible pressure chamber having a movable wall of substantially greater area than the maximum effective cross sectional area of said core, means connecting said chamber in pressure-responsive relation to said venturi, and means 65 connecting said core to said wall for Venturi-controlling operation thereby.

5. In combination, a variable venturi comprising a conduit member and a core member mounted for relative movement to vary the effectiveness 70 of said venturi, a double-acting expandible pressure chamber connected in pressure-responsive relation to said venturi and having a low pressure end, a high pressure end and a movable wall, means extending into said high pressure 75

end and operatively connecting said movable wall to the movable one of said members.

6. In combination, a conduit adapted to conduct fluid flow in one direction, a movable Venturi-control core within said conduit; said conduit and core being relatively formed and positioned to leave therebetween a Venturi passage expanding gradually in the direction of fluid flow from a constricted throat to a relatively unconstricted passage, and said conduit and core being relatively tapered and positioned to decrease constriction of said throat as the core is moved counter to said direction of fluid flow; an expansible pressure unit including a pressure chamber and a pressure-wall movable in response to change of pressure therein, a pressure connection from the throat of said venturi to the chamber of said expansible pressure unit, and means connecting said Venturi-control core to the movable wall of said expansible pressure chamber for actuation thereby.

7. In combination, an expansible pressure unit including a pressure chamber and a pressure-wall movable in response to change of pressure therein, a movable core member, connecting means connecting said core member to the movable wall of said expansible pressure chamber for longitudinal movement thereby, a conduit surrounding said core member; said conduit and core member being relatively formed positioned and tapered to leave a Venturi passage with characteristic constricted throat therebetween; the relative position, taper and direction of taper between said conduit and core member being such that movement of said core in a direction toward said connecting means decreases the throat constriction of said Venturi passage.

8. An automatically variable venturi including, a venturi comprising, a conduit adapted to conduct fluid flow in one direction and a movable Venturi-control core within said conduit; said conduit and core being relatively formed and positioned and tapered to leave therebetween a Venturi passage expanding gradually in the direction of fluid flow from a constricted throat to a relatively unconstricted passage, and said conduit and core having their relative taper positioned and directed to decrease constriction of said throat as the core is moved counter to said direction of fluid flow; and a differential expansible pressure chamber comprising a chamber and a movable pressure wall dividing said chamber into low and high pressure compartments; said movable pressure wall being larger than the cross-section of said core and having substantially equal pressure-effective areas on both sides; a low pressure passage from the throat of said venturi into said low pressure compartment, a high pressure passage from said venturi at a relatively unconstricted portion thereof into said high pressure compartment,

ment, connecting means extending through said high pressure passage and connecting said core to said movable wall for actuation thereby, and force-exerting means tending to urge said movable wall toward the high pressure compartment of said chamber regardless of whether or not pressure exists therein.

9. A variable venturi comprising a conduit and core therein, relatively shaped and positioned to form a Venturi passage therebetween, part of 10 which passage is relatively free and part of which passage is relatively constricted to a throat, a double-acting expansible pressure chamber having a low pressure end, a high pressure end and a movable pressure-wall therebetween, said chamber being positioned with its high pressure end nearer than its low pressure end to the throat of said Venturi passage, means connecting said core to said movable wall for actuation thereby, and means connecting said chamber into pressure-responsive relation with said Venturi passage.

10. In combination, a variable venturi having a passage tapering gradually to and from a constricted throat, adapted to conduct fluid flow in either direction, movable Venturi-control means 25 associated with said venturi for altering the effectiveness thereof, and flow-responsive means for moving said Venturi-control means substantially similarly in response to change of flow in either direction through said venturi.

11. In combination, a variable venturi comprising a conduit member and a core member mounted for relative movement to vary the effectiveness of said venturi, a double-acting expansible pressure chamber connected in pressure-responsive 35 relation to said venturi and having a low pressure end, a high pressure end, and a movable pressure wall therebetween, with substantially equal pressure-effective areas exposed on its low and high pressure sides, and means operatively connecting 40 the movable one of said members to said movable wall for actuation thereby.

12. In combination, a conduit having a passage part of which is relatively free and part of which is relatively constricted to form a throat, a double-acting expansible pressure chamber having a low pressure end, a high pressure end and a movable wall therebetween, with substantially equal pressure-effective areas on its low and high pressure sides, a lead connecting the low pressure end 45 of said chamber into pressure-responsive relation with said constricted throat, a lead connecting the high pressure end of said chamber into pressure-responsive relation with a relatively free part of said passage, and means controlled by said movable wall for altering the constriction of said throat.

EUGENE JACOBSON.
